UNITED STATES PATENT OFFICE

169,685

ELECTROSTATIC STORAGE UNIT

George H. Kress, Endwell, N. Y., and Carl W. Sundberg, Detroit, Mich., assignors to International Business Machines Corporation, New York, N. Y., a corporation of New York

Application December 18, 1952, Serial No. 22,761

Term of patent 14 years

(Cl. D26—5)

To all whom it may concern:

Be it known that we, George H. Kress, and Carl W. Sundberg, citizens of the United States of America, residing respectively at Endwell, county of Broome, State of New York, and Detroit, county of Wayne, State of Michigan, have invented a new, original, and ornamental Design for an Electrostatic Storage Unit, of which the following is a specification, reference being had to the accompanying drawings forming part thereof.

Fig. 1 is a perspective view of an electrostatic storage unit, embodying our design.

Fig. 2 is a front elevation of the same.

Fig. 3 is a side elevation of the same as seen from the right end.

Fig. 4 is a plan view of the same.

Fig. 5 is a rear elevation of the same.

The left side of the electrostatic storage unit is plain.

We claim:

The ornamental design for an electrostatic storage unit, as shown and described.

GEORGE H. KRESS.
CARL W. SUNDBERG.
